UNITED STATES PATENT OFFICE

BARON DE CURTIN DENNISTON, OF OAK BLUFFS, MASSACHUSETTS

NOISE-MAKING TOY

Application filed January 8, 1930. Serial No. 419,344.

This invention relates to improvements in toys, and has particular reference to a safe explosive or noisemaking toy.

The primary object of the invention relates in a toy for the firing of firecrackers to prevent injury and loss of life to the person setting off the same. It is understood that a certain degree of danger exists in the shooting of firecrackers, and it is my invention to provide a device which may be held in the hand of a person and in which the firecracker may be placed, the fuse of which is ignited by the lighting of a match, and which match is ignited by the actuation of a lever remotely positioned with respect to the match and the firecracker.

Another object of the invention is to provide an explosive toy which embodies a hollow container mounted at one end of a stick for the reception of a firecracker, one end of which is closed by a hinged cover adapted to be blown open upon the explosion of the firecracker, thus producing a loud report.

A further object is the provision of an explosive toy which is simple of construction, safe in operation, and amusing and entertaining to the operator.

With these and other objects in view the invention resides in the certain novel construction, combination, and arrangement of parts, the essential features of which are hereinafter fully described, are particularly pointed out in the appended claims, and are illustrated in the accompanying drawings, in which:

Figure 1 is a perspective view of my toy in use.

Figure 2 is an enlarged side elevational view of the same.

Figure 3 is an enlarged vertical longitudinal sectional view.

Figure 4 is a vertical transverse sectional view on the line 4—4 of Figure 3.

Figure 5 is an end elevational view with parts broken away.

Referring to the drawings by reference characters, the numeral 10 designates my improved firecracker toy in its entirety, which includes an elongated stick 11, one end of which is shaped to provide a handle 12, while

fixed to the opposite end is a can or cylinder 13, the outer end of which is open but which may be closed by a cover or lid 14 hinged to the cylinder as at 15. The can or cylinder 13 is attached to the stick 11 by straps or brackets 16. The closed end of the cylinder 13 is provided with an opening 17 which registers with an opening 18 provided in the adjacent end wall of a housing 19 fixedly mounted to the stick 11 by bolts or the like 20. The housing 19 is disposed next to the closed end of the cylinder 13, and the openings 17 and 18 align so as to establish communication between the interior of the cylinder and the interior of the housing 19.

One side of the housing 19 is open and hinged to the open side is a door 21 hinged as at 22 to the housing for swinging movement from an open position to a closed position. Contractile springs 23 have their respective ends connected to the inside of the door 21, and to the opposed wall of the housing and normally tends to swing the said door to a closed position. The door 21 is provided with a suitable means for supporting a match 24, and which means includes an opening 25 provided in the door, while a rubber strip 26

fixed to the inner side of the door and provided with a distendable opening 27 which registers with the opening 25, whereby a match inserted through the openings 25 and 27, will be held by the contraction of the walls of the opening 27 about the match stick. The match 24 is inserted into the match holding means so that the head of the match is disposed on the inner side of the door so as to present the head of the match in a position to be engaged by a friction strip 28 fixedly mounted within the housing 19 as at 29. The friction strip 28 is of a flexible material, but is normally disposed in the path of the head of the match 24 so that when the door 21 is swung to a closed position by the action of the spring 23, the head of the match will scratch upon the friction surface 28 and become ignited.

The friction strip 28 is located in a position so that when the door is in a fully closed position and the match 24 is lighted, the flame from the match will be disposed adjacent the opening 18 in the end wall of the

housing to light the fuse of the firecracker 30 adapted to be placed in the cylinder or can 13 through the open end thereof, it being understood of course that the hinged cover 14 is first swung to an open position.

For the purpose of holding the door 21 in an open position against the action of the spring 23, I provide suitable catch means which includes an eye 31 on the outer side of the door which is engageable with a hook 32 pivoted to one side of the stick 11 as at 33. The hook 32 intermediate its ends is pivotally connected to a link 34 which in turn is operatively connected to a lever 35 pivoted to the stick 11 as at 36. From the foregoing description, it will be seen that when the door 21 is swung to an open position as shown in Figure 4 of the drawings, and the hook 32 engaged with the eye 31, the said door will be held open against the action of the spring 23. Assuming that the firecracker has been inserted into the cylinder 13 in the manner hereinbefore mentioned, and the fuse from which extends into the housing through the opening 18, and a match 24 has been placed in position upon the door, an operator pulling backward upon the lever 35 will cause the hook 32 to disengage the eye 31, thus the springs 23 will rapidly swing the door to a closed position, and in so doing the head of the match 24 striking the friction surface 28 will become lighted, and in turn will light the fuse of the fire cracker 30. In order to admit atmospheric air to the interior of the housing to facilitate combustion of the match and the fire cracker, the said housing 19 may be provided with air openings 37, while a match holder 38 may be mounted upon the stick for the carrying of a box of matches for use as and when desired.

When the cover 14 is in a closed position, the explosion of the fire cracker within the cylinder 10 will cause the said door to fly open, and at the same time produce a loud report. After each explosion of the fire cracker, the same may be emptied from the can or cylinder 13, and a fresh one inserted and the door and parts moved to a set position for a repeat operation. From the construction herein shown and described, it will be understood that I have provided a simple and safe fire cracker toy for persons when setting off fire crackers as it is unnecessary for the hand of an operator to come in contact with the lighted match or the fire cracker to be exploded. A toy of this character will be found useful in various celebrations, and will prevent injury and loss of life to the person setting off the explosive.

Having thus described the invention, what I claim as new and desire to secure by Letters Patent is:—

1. A fire cracker toy comprising a stick, a hollow container mounted at one end thereof and being open at one end, a cover on the

open end of said container, the end wall of said container having an opening therein, a housing mounted on said stick adjacent said container with the interior of the same in communication with the interior of said container through an opening provided in said housing whereby the fuse of a fire cracker placed in said container may extend through said opening in said housing, a spring actuated door for closing one side of said housing, a friction strip mounted within said housing, and match holding means carried by said door for supporting a match with its head in the path of said friction strip whereby movement of said door from an open to a closed position will cause a match to be ignited and the flame therefrom will light the fuse of a fire cracker.

2. A fire cracker toy comprising a stick, a hollow container mounted at one end thereof and being open at one end, a cover on the open end of said container, the end wall of said container having an opening therein, a housing mounted on said stick adjacent said container with the interior of the same in communication with the interior of said container through an opening provided in said housing whereby the fuse of a fire cracker placed in said container may extend through said opening in said housing, a spring actuated door for closing one side of said housing, a friction strip mounted within said housing, and match holding means carried by said door for supporting a match with its head in the path of said friction strip whereby movement of said door from an open to a closed position will cause a match to be ignited and the flame therefrom will light the fuse of a fire cracker, and catch means for holding said door in an open position against the action of said spring.

3. A fire cracker toy comprising a stick, a hollow container mounted at one end thereof and being open at one end, a cover on the open end of said container, the end wall of said container having an opening therein, a housing mounted on said stick adjacent said container with the interior of the same in communication with the interior of said container through an opening provided in said housing whereby the fuse of a fire cracker placed in said container may extend through said opening in said housing, a spring actuated door for closing one side of said housing, a friction strip mounted within said housing, and match holding means carried by said door for supporting a match with its head in the path of said friction strip whereby movement of said door from an open to a closed position will cause a match to be ignited and the flame therefrom will light the fuse of a fire cracker, and manually operable means for operating said catch means for releasing said door from an open position.

4. A fire cracker toy comprising a stick, a hollow container mounted at one end thereof and being open at one end, a cover on the open end of said container, the end wall of said container having an opening therein, a housing mounted on said stick adjacent said container with the interior of the same in communication with the interior of said container through an opening provided in said housing whereby the fuse of a fire cracker placed in said container may extend through said opening in said housing, a spring actuated door for closing one side of said housing, a friction strip mounted within said housing, and match holding means carried by the door for supporting a match with its head in the path of said friction strip whereby movement of said door from an open to a closed position will cause a match to be ignited and the flame therefrom will light the fuse of a fire cracker, an eye on said door, a hook pivoted to said stick for engagement with said eye for holding said door in an open position, an actuating lever pivoted to said stick, and a link operatively connecting said lever with said hook for moving said hook out of engagement with said eye upon actuation of said lever to allow said spring to swing said door from an open to a closed position.

5. In an explosive toy, means for supporting an explosive article to be exploded, igniting means for igniting the explosives held by said first means, said igniting means including a hinged member, match holding means provided thereon, and a fixed friction strip disposed in the path of movement of the head of a match held by said match holding means upon movement of said hinge member.

6. In an explosive toy, means for supporting an explosive article to be exploded, igniting means for igniting the explosive held by said first means, said igniting means including a hinged member, match holding means provided thereon, a fixed friction strip disposed in the path of movement of the head of a match held by said match holding means upon movement of said hinge member, spring means acting upon said hinged member to swing the same in one direction, and catch means for securing said hinged member in a position against the action of said spring means.

55 In testimony whereof I affix my signature.
BARON DE CURTIN DENNISTON.
